UNITED STATES PATENT OFFICE.

VERNON LEE GIBSON, OF SHOLES, NEBRASKA.

CYLINDER-HEAD LIFTER.

Application filed October 13, 1921. Serial No. 507,505.

To all whom it may concern:

Be it known that I, VERNON L. GIBSON, a citizen of the United States, residing at Sholes, in the county of Wayne and State 5 of Nebraska, have invented certain new and useful Improvements in Cylinder-Head Lifters; and I do hereby declare the following to be a full, clear, and exact description of the invention, such as will enable others 10 skilled in the art to which it appertains to make and use the same.

The present invention relates to a lifting device adapted especially for use with the cylinder heads of automobile and other internal combustion engines, more particularly 15 the engines of Ford automobiles, although the device can be used for other engines and purposes for which it is suited.

It is the object of the invention to provide a simple and practical device of novel construction adapted to be attached to the cylinder head of an engine for conveniently lifting the cylinder head.

With the foregoing and other objects in view, which will be understood as the description proceeds, the invention resides in the construction and arrangement of parts, as hereinafter described and claimed, it being understood that changes can be made 30 within the scope of what is claimed, without departing from the spirit of the invention.

The invention is illustrated in the accompanying drawing, wherein—

Fig. 1 is a plan view of the device as applied to a cylinder head of an engine.

Fig. 2 is a perspective view of the device.

Fig. 3 is an elevation of the device, portions being shown in section.

The device includes a horizontal handle 40 4 to be disposed longitudinally above the cylinder head, and portions 5 extending at an angle from the ends of the handle 4 and disposed horizontally or transversely. Terminal portions 6 extend downwardly 45 from the transverse portions 5, and constitute the terminals of a rod or other member from which the handle 4 and portions 5 and 6 are formed. The handle portion is offset transversely or to one side of the vertical 50 plane of the vertical terminal portions 6.

In order to attach the portions 6 to the cylinder, screw-threaded plugs 7 are rotatably mounted on said portions 6 and have

heads 8 at their upper ends for the engagement of a wrench or other implement for 55 screwing the plugs 7 into the threaded holes in the cylinder head in which the spark plugs 9 or other plugs are ordinarily secured. Retaining nuts or members 10 are threaded on the terminals 11 of the portions 60 6, and said nuts are tapered so as to readily enter the holes in the cylinder head.

In using the device, the two intermediate spark plugs are removed, and the plugs 7 are screwed down into the holes from which 65 the spark plugs were removed, the portions 6 being spaced apart the distance between such holes in order that the plugs 7 can be readily screwed into such holes. The device is disposed with the handle 4 offset inwardly 70 to be disposed substantially over the longitudinal center line of gravity of the cylinder head, whereby the handle 4 in being grasped by the hand will enable the cylinder head to be lifted conveniently, without tilting to one side or the other or binding on the anchor bolts which fasten the cylinder head in place. The nuts or members 10 will prevent the portions 6 from pulling out of 75 the plugs 7, when lifting the cylinder head, it being noted that the portions 6 are 80 slideable in the plugs so that the plugs can be screwed and unscrewed individually when applying and removing the handle. By using the present device, the cylinder head can 85 be lifted off and applied to the cylinder block without injuring the cylinder head gasket, or other parts, and will eliminate the cumbersome handling of the cylinder head 90 as when lifting and handling the same without the aid of a lifter of the present kind.

Having thus described the invention, what is claimed as new is:—

1. A cylinder head lifter comprising a handle having downwardly extending terminal portions, screw plugs rotatable and slideable on said terminal portions to be individually engaged in and disengaged from the spark plug or similar holes in a cylinder head, and retaining members on 100 said terminal portions under said plugs.

2. A cylinder head lifter comprising a handle having downwardly extending terminal portions, screw plugs rotatable and slideable on said terminal portions to be individually engaged in and disengaged from 105

the spark plug or similar holes in a cylinder head, and retaining members on said terminal portions under said plugs, the intermediate portion of said handle being bent
5 at a right angle with said terminal portions and extending to one side.

In testimony whereof I have signed my

name to this specification in the presence of two subscribing witnesses.

VERNON LEE GIBSON.
